CLAIM

The ornamental design for audio system pedestal, substantially as shown and described.

DESCRIPTION

FIG. 1 is an exploded perspective view of an audio system pedestal showing our new design;

FIG. 2 is an exploded front view thereof;

FIG. 3 is an exploded rear view thereof;

FIG. 4 is a top view of pedestal;

FIG. 5 is a bottom view thereof;

FIG. 6 is an exploded side view thereof; and,

FIG. 7 is another exploded side view thereof.

The broken lines represent environmental structure only and form no part of the claimed design.
